SLOT MECHANISM

Edwin J. Brown, New York, N. Y.

Application October 24, 1932, Serial No. 639,266

6 Claims. (Cl. 194—1)

This invention relates to a slot mechanism; more particularly to a dispensing slot mechanism, also called a vending machine. Such apparatus, when actuated by the proper token or tokens, dispenses goods, a package for instance, or performs some service of function in consideration of the tokens.

Apparatus of this kind has always presented certain problems in respect to checking the token as to whether it is the correct token for the goods or service given, and as to actuation by a number of tokens of a given value, when more than one token is to be given or paid for a certain package of goods or a certain service.

15 The token may be incorrect inasmuch as it is wrong or is false. In the following I shall distinguish between false and wrong tokens in the following manner: The currency used in a certain country may comprise coins of different denominations, but the slot mechanism is to respond to only one coin of particular value, a specific token of a specific denomination. If the customer by error or mistake wants to insert any other coin or token but that for which the mechanism is intended, such a coin or token is a "wrong" token.

20 Slot mechanisms however very frequently are abused, an effort being made to actuate such mechanism by a counterfeit coin or a slug, possibly similar in size to the correct token, but of less value. Incorrect tokens of that kind I shall hereinafter call "false" tokens.

It is one object of this invention to provide a slot mechanism which refuses wrong tokens, in such manner that they cannot be inserted into the machine or mechanism at all.

Another object of this invention is to eliminate false tokens from the correct tokens and either to reject them or temporarily retain them, 40 and to actuate an alarm in order to draw attention generally to the fact that an attempt has been made to actuate the slot mechanism by a false token.

If an attempt is made to abuse the slot mechanism by wrong tokens, and the party making such an attempt manages to insert a wrong token such a wrong token should also,—and it does in this invention,—actuate an alarm.

A further object of this invention is to provide means returning to the user of a slot mechanism, which is to be actuated only by a certain number of tokens, an insufficient or excess number of such tokens inserted by the user; if for instance a slot mechanism is built to dispense a package when three tokens are in-

serted, but only two or one have been inserted, the two or one tokens are rejected, and returned to the user; if four tokens are inserted the dispenser is actuated and the one excess coin is returned.

5 A further object of this invention is to provide means permitting the ready change of a slot mechanism from one denomination of tokens to another intended denomination of tokens.

Still another object of this invention is to provide a slot mechanism in which component parts, which may have to be exchanged at times, may readily be detached from the body of the apparatus and be replaced without complicated disassembling or reassembling operations.

10 One further object of this invention is to provide a mechanism which cannot be clogged up, or blocked, or put out of operation by the insertion of foreign matter. It is also an object of this invention to provide an apparatus which 15 performs quickly and with certainty the operation of separating the correct, the false and the wrong tokens, and the wrong change, which at the same time however responds immediately to the correct token and to the correct number of 20 tokens.

Another object of this invention relates to quick adjustment of a mechanism of this kind for the dispensing of wares, packages or goods of different sizes.

25 Additional objects of this invention will be elucidated in the following description as explained by the accompanying drawings in which—

Fig. 1 is a sectional, sectioned elevation of the 30 mechanism of my invention.

Fig. 2 is a similar rear elevation of my invention.

Dot-dash lines, arrows and corresponding numbers explain in the foregoing figures the 35 direction in which the views of the other figures are taken respectively.

Fig. 3 shows a fractional top view of the device of my invention, the top part and covering having been removed.

Fig. 4 shows a fractional front elevation of the 40 device of my invention.

Fig. 5 shows a perspective view of the adjustable means used for the goods to be dispensed.

Fig. 6 shows a partial side view of the selector 45 in the normal starting portion actuated by a token.

Fig. 7 shows a selector in a corresponding view in an intermediate operating position.

Fig. 8 shows the selector in a corresponding 50

view in the position of extreme clockwise rotation.

Fig. 9 shows the selector in a corresponding view but in an intermediate operating position operated by a false token.

5 The corresponding view of Fig. 10 shows a selector plate in a position slightly advanced from that of Fig. 9.

Fig. 11 shows a partial bottom view of the selector illustrating the selective dispensation of 10 correct tokens.

Figs. 12 and 13 are detail cross-sections, taken in directions normal to each other as indicated in Fig. 10 and serving to show the means for elimination of false tokens.

15 Similar numerals refer to similar parts throughout the various views.

One of the important features of my invention, as mentioned above, is the adaptability of 20 my device for various tokens and various multiples of tokens. For the purpose of the accompanying exemplary illustrations I have selected a device adapted to be actuated by a pair of tokens; but anybody acquainted with this art will 25 readily understand that the device may be arranged to receive any multiplicity of tokens of any different denominations, and that it can readily be changed from one plurality to the other and from one denomination to the other. The machine is provided with an intake I in 30 which the token is inserted and passes,—if not refused as a wrong token,—into a selector in the housing H. The selector comprises a plurality of selector plates, which were already referred to above, several detailed views explaining the 35 action of said plates P. If the correct coin has been received in the selector plates, a transmitter T is actuated and transmits the force of manipulation applied to the selector to the dispenser D, which dispenses goods as delivered 40 thereto from an elevator E. When the wrong tokens are refused at the intake I they drop into a pocket W on top of the housing H. When 45 false tokens have been inserted into the mechanism or the wrong number of tokens has been inserted thereinto they are rejected by the mechanism, and respectively are passed to the false token pocket F or refund pocket R or they may be passed into one and the same pocket. When 50 the correct amount of correct tokens has been inserted into the mechanism, and the goods are duly dispensed, said tokens are deposited in a collection pocket C which is arranged upon the rear of base B. The mechanism shown in the drawings may form part of a larger cabinet, said 55 collection pocket C being disposed upon the inside of said cabinet. When no such cabinet is used but the device is simply mounted on the top of the base B which in that case is a column, the collection pocket C is of course arranged 60 upon the inside of such a column. Tokens will be identified in the following by the letter O to which numerals are affixed in the order in which they are referred to.

Such a token O1 is shown to be inserted in 65 Fig. 1 in a slot 21,—of the width of said token,—provided in the curved outer wall 22 extending over the front, back and top of the intake I. The coin inserted in the slot 21 strikes a lever 23, which is fulcrumed upon a pivot 24 extending between the free ends 25 of levers 26. The levers 26 are laterally displaced upon either side of slot 21 and are fulcrumed upon a rod 27, rotating thereon, near the base of the intake I. The levers 26 are normally pulled frontwardly by a tension spring 28. The token O1 rests upon a

false bottom 29, which extends from the lower front end backwardly, and is disposed substantially concentric to the rod 27 where the token O1 rests thereupon.

A short distance behind said coin the said false 5 bottom 29 is slanted and then extends straight down into the housing H along the path of the token rolling thereover into the housing H as indicated by tokens O2 and O3. Upon the back part of the wall 22 is disposed a channel 30, 10 which may be slightly spread at its top end receiving O1 and guiding it down as it follows the slope of false bottom 29. I prevent the insertion of a token which is larger than the correct token by limiting the width of slot 21 15 accordingly and by gauging the height of said slot above the false bottom 29 so as just to allow the correct coin to be inserted.

The correct token O1 having thus been inserted, it strikes the downward extension 31 of 20 lever 23 and begins to swing the said lever around the pivot 24. But immediately the toe 32 extending from the front of lever 23 engages upon the circumference of the token and prevents further swinging of lever 23 around pivot 24. When 25 the token O1 is further pushed by the operator into the intake I,—the swinging of lever 23 having been blocked,—it pushes the levers 26 back, sliding over the concentric part of the false bottom 29, until it slides onto the slanted part of 30 said bottom, whereupon the lever 23 is allowed to swing out of its blocked position and the token passes into the position O2 where it is engaged on its free end in the channel 30, and then drops down.

35 The positions into which the levers 23 and 26 were pushed by the tokens thus passing into the housing are indicated at 23a and 26a.

If the token,—which the operator intends to 40 insert in the intake I,—is smaller than the correct token, it also strikes the extension 31 of lever 23, and swings said lever back. But the circumference of said token is not immediately engaged upon by the toe 32 in the manner of the correct token, and therefore the lever 23 swings 45 a certain distance in clockwise direction around pivot 24 until the lug 33 on said lever strikes the wall 22. But the small wrong token cannot push back the lever 26, such pushing back of said lever being blocked by the interference of a downward 50 extension 34 of wall 22 with lug 33. The small wrong token can therefore not be inserted; it is refused by the machine and drops into the wrong token pocket W on top of housing H. The 55 distance of the wall 22 above and the extension 34 in back of lug 33 are slightly exaggerated for purposes of perspicuity. These dimensions may be limited in such a manner that nothing but just the correct token brings about any substantial movement of the levers, a small wrong token causing immediate blocking of lug 33 against wall 22 and extension 34. The intake is mounted upon the top of the housing and may be replaced if the parts are to be adjusted to different sizes of tokens or if a different number of tokens are 60 to be received thereby. In the drawings the intake is arranged to receive two tokens as explained above. The two slits of the insert are shown to be separated in the drawing by a heavier central partition 35; aforesigned parts of the 65 intake are substantially symmetrically duplicated on either side of said partition.

70 After having passed from the intake into the housing, the token O3 is guided by channel 30 into one of the selector plates P. In the present 75

invention one such plate is provided for each one of the number of tokens which are to be received by the machine for one actuation; the drawing showing the machine exemplarily to be adapted for two tokens, there are two plates P rigidly mounted upon a shaft 40. Each plate P comprises a disc 41 and a cover 42 on said disc which is partly sectioned away in Fig. 1. The cover 42 is substantially semi-circular, covering about half of disc 41. Upon opposite sides rods 43 and 44 clamp together the various plates and thereby the respective discs 41 and covers 42.

The shaft 40 is suitably journaled, rotatably but endwise stationarily, upon housing H and carries on one end the crank 47 with handle 48. The crank handle 47 has upon the opposite side of shaft 40 an extension 49 which is normally pressed by the tension of spring 59 against the stop pin 45. The angular movement of crank 47 is limited in the opposite direction by a stop pin 46. One of plates P, the last plate P1 to the right seen from the front of the machine, carries an annular sector 51, which is attached to said plate, and which is serrated near its front end 52 and its rear end 53. A double pointed pawl 54 is mounted upon a stud 55 extending from one side wall of the housing H and is in operative alignment with the sector 51. A tension member 56 extending from a slot in said pawl into a correspondingly slotted lug 57 on said wall of housing H normally retains the pawl in the position shown in Fig. 1. When the movement of the crank 47 is begun, the plates P mounted on shaft 40 being rotated thereby, pawl 54 is brought into operative engagement with the serrations 52 of sector 51, so that the crank 47 cannot return into its normal position, unless the plates are rotated so far, that the pawl 54 slides off the other end of sector 51. The pawl 54 slides off the said other end in this manner when the crank 47 has been pushed back so far that the extension 49 strikes pin 46. The pawl then snaps back into its normal position of Fig. 1. In a similar manner the return motion of crank 47 must necessarily be carried through until the plates are again in the position of Fig. 1, because the other point at the end of pawl 54 engages upon serrations 53 and 52, so that the operator must complete the return stroke. It is important for the operation of this machine, that the front and back stroke of the crank cannot be partly repeated on account of the serrated sectors 51, because otherwise a return of a token may be brought about after the package has been delivered, and the machine could be otherwise tampered with.

The disc 41 of the plate (Figs. 1, 6, 7, 8, 9 and 10) is provided with a groove 60 extending across one face thereof, offset from the shaft 40, said groove facing the cover 42. One end of said groove faces the bottom end of intake I, when the extension 49 of handle 47 is in its position of rest against pin 45. Transversely to the machine the said groove is also in alignment with the channel 30. The token in passing through the intake drops therefore into the one end of groove 60,—and rolls into the position of token O4 of Fig. 6. Upon the face of disc 41 is rotatably fulcrumed on pivot 61 a three armed lever 62. One arm 63 of said lever extends between disc 41 and cover 42 and swingably carries at its free end a gauge 64 on a pin 65. The pin 65 extends into a slot 66 in clearance groove 59 of disc 41 which limits the rocking motion of arm 63. The gauge 64 is provided with a concavely disposed edge 67 on one side of pin 65, the said edge fitting substantially

around the circumference of the correct token O4. Whereas normally the spring 68 pulls the arm 63 together with the lever 62 in a clockwise direction down,—the gauge 64 hanging straight down due to gravity,—the said arm 63 is swung slightly 5 in counter clockwise direction around pivot 61 by an approaching token O4, the force of gravity and of travel of said token forcing it to slide underneath and lifting the concave edge 67 of gauge 64.

Another arm 69 of lever 62 carries a roller 70 10 on its free end which is engaged upon a finger 71 when the plate is in the position of Fig. 6, before the token O4 slides into the position shown. When the said token slides into position, the said roller 70 is lifted off finger 71 into the position 15 shown in the drawings.

The third arm 72 of lever 62 is provided with notches 73 and 74 at its end, which are slantedly arranged in the manner of steps. Through the various plates P rotatably extends a shaft 20 75, upon which are fixedly mounted a plurality of pawls 76, one pawl for each plate of the selector. Said pawls are in operative alignment with arms 72. When the lever 62 has been swung in counterclockwise direction by token O4 in the 25 manner of Fig. 6, the step 73 of arm 72 is swung out of the range of pawl 76, said pawl therefore dropping into notch 74, when it is allowed to swing in counter clockwise direction, as shown in Fig. 7 if lever 62 is not blocked in the counter 30 clockwise direction and as will be explained below. But if the tokens are rolled into groove 60 without sufficient force and momentum to swing the lever 62 into the position of Fig. 6, the pawl 76 will not drop into notch 74 when swung in 35 counter clockwise direction, but will drop into notch 73. The pawl is lodged in notch 73 in Figs. 9 and 10, the false token O6 of Fig. 9 being of less weight than the correct token and having on that account been unable to swing lever 62 40 to such an extent in counter clockwise direction, that the pawl 76 falls into notch 74.

The shaft 75 carries on its right end a drag lever 77. The said lever is pulled in counter-clockwise direction by a spring 78 hooked onto 45 the end of rod 43. The drag lever 77 is provided at one free end with a roller 79, which is engaged in the position of Fig. 6 upon a finger 81 similar to finger 71. While the roller 79 is engaged upon fingers 81, the pawl 76 is prevented from engaging upon arm 72. But when the plates P are rotated by crank 47, the drag lever 77 is free to follow the tension of spring 78 and drops either into notch 74,—when the correct coin has properly swung the lever 62 in clockwise direction, or into notch 73 when there is no token in groove 60, or when the token is of insufficient weight, like the false coin O6.

Upon the shaft 40 idles a lever 80, with two arms 82 and 83. Arm 82 is provided with a lug 60 84, which extends into operative alignment with a hook 85 on the end of drag lever 77. The said hook engages the lug 84 on arm 82 upon rotation of the plate P provided the pawl 76 is lodged in notch 74 of lever 62. But the said hook will 65 not engage upon lug 84,—will swing past said lug as shown in Figs. 9 and 10,—when pawl 76 is lodged in notch 73 of lever 62. Of course each lever 62 of each plate P making up each set of plates of one selector may be differently positioned in respect to pawl 76, according to whether a proper token is lodged in the respective groove 60, or no token, or an underweight token is retained in the respective groove. All the pawls 76 are however mounted on the same shaft, so 75

that none of them can drop into notch 74, if one drops into notch 73, the said one pawl engaged upon said one notch 73 preventing further counter clockwise rotation of shaft 75. Unless therefore all grooves 60 contain correct tokens, hook 85 on drag lever 67 cannot engage upon lug 84 on lever 80. Since actuation of lever 80 eventually serves to transmit the power of manipulation to the dispensing parts of the device, the device is not actuated and no dispensation can take place unless the full amount of correct tokens are placed into the machine.

A short distance back of hook 85, a tooth 86 extends in the same direction from drag levers 15 71. The said tooth engages upon lug 84,—after lever 80 has been swung to an extreme position in clockwise direction by the hook 85 when handle 84 is released and the selector plates return to their normal position of Figs. 1, and 6, lever 20 80 thus also being swung back into its normal position.

The second arm 83 of idle lever 80 is omitted in Figs. 6, 7, 8, 9 and 10, but its operation may be followed in the views of Figs. 1, 2, 3 and 11. Arm 25 83 transmits the motion imparted by way of lug 84 to lever 80. The free end of arm 83 is connected by a link 87 to one arm of angle lever 88. The said angle lever is fixedly mounted upon shaft 89, which is journaled in housing H, and lever 88 is thus fulcrumed upon the housing. The other arm 90 of angle lever 88 extends down upon one side of the housing and a lever 91 shaped similar to said arm 90 extends substantially parallel thereto down upon the other side of the housing 35 from shaft 89. The shaft 89 is tensioned in clockwise direction by a spring 92 coiled thereon, so that a lug 93 on arm 90 normally rests against the rubber ring 94 extending around an eccentric 40 95 mounted on rod 96, which extends across housing H and is angularly adjustable thereon. By angular adjustment of rod 96, the normal position of rest lever 88 may therefore be changed as required.

Studs 97 coaxially extend from the free ends of arm 90 and lever 91, towards each other and detachably carry the end of a substantially horizontally and longitudinally movable carriage 98. The said carriage consists of two flat members 99 which are hinged upon the studs 97, the said 50 members being spaced apart in parallelism by rods 100 and 101. Upon the ends of rod 101 are rotatably mounted the rollers 102, which travel back and forth on suitable tracks 103 extending from the side walls of the housing H when the parts 83, 87, 88 and 98 of transmitter T are rocked by the motion transmitted thereto from shaft 40 by reason of the engagement of drag lever 71 on idler lever 80. Upon rods 100 and 101 is mounted between members 99 a lug 104 55 which serves to engage upon goods delivered thereto by the elevator E, presently to be explained, to push said goods to the front of the machine and to dispense them through the delivery opening D so that they drop onto a shelf 105. There is also a slotted member 106 slidably disposed upon rods 100 and 101. It is suitably connected to a counting device, not shown, which registers the number of articles dispensed.

The delivery opening D is surrounded by side 70 walls 107 and a ceiling 108 for a certain distance back into the device, said walls and ceiling forming a duct which is closed at its rear end by a door 109. That door is hinged upon and depends from a transverse rod 110. The 75 upper end 111 of the wall of the door extends

above the rod 110 and is normally engaged by a nose 112 extending down from a lever 113 which is fulcrumed upon a rod 114 transversely supported in the housing. The lever 113 normally rests upon one of the tracks 103 and its 5 end 115 is bent up—from the point where the lever rests on track 103—past and into slidably engagement upon rod 101. Rocking of the carriage 98 will therefore swing the lever 113 up and down. When the lug 104 is advanced with 10 the carriage 98 and pushes ahead the article to be delivered, the nose 112 is lifted out of engagement with the end 111 of the wall of door 109; the said article engages upon the door 109 and swings it up, out of its way so that the article may be 15 delivered. But in the normal position of the parts the nose 112 prevents tampering with the machine inasmuch as it locks the door 109, preventing a frontward opening of said door and thereby preventing an unauthorized removal of 20 articles from the top of the elevator, behind the said door.

The elevator E depends from transverse angles 116 and 118, respectively disposed in the front and the back of the machine. The flat ends 117 25 of said angles are inserted and clamped between the housing H and the base B. The vertical part of the angle 118 is upwardly continued by angle 119, which extends substantially in alignment with the front of lug 104 or is disposed to the 30 front thereof, when the latter is in its normal position of rest. From the angle 118 extend down, substantially in alignment with the front thereof, the rear elevator rods 120, which are bridged at their lower ends by a plate 121. In 35 Fig. 5 rods 120 happen to be hidden behind rods 123 and 135.

A door 122 forms part of the front angle 118, and is swingable into and out of alignment with the back of said angle. From the said door extend down the front elevator rods 123 which are connected at their lower ends by the plate 124. The plate 124 is hinged upon the floor plate 125 of the elevator by means of a knurled screw 126 which is in alignment with the fulcrum of the 45 door 122. The door 122 may be secured in a locked position by the screw 127. A second knurled screw 128 extends through a frontward slot in floor plate 125 into plate 124. After screw 127 has been removed and knurled screw 128 has 50 been loosened up, the rods 123 extending between door 122 and plate 125 may be swung upon frontwardly, permitting the placement of a stack of goods between the other vertical rods of the elevator. A screw 129 extends through the center of 55 plate 121, through a longitudinal slot 130 of floor plate 125, and serves to fasten plate 121 on the latter.

On top of the transverse angles 116 and 118 are mounted the longitudinal angles 131 and 132 to 60 the left and to the right of the elevator. They are fastened upon the transverse angles by screws 133 and 134, which respectively extend through transverse and through longitudinal slots in the horizontal parts of the angles 131 and 132. 65 Whereas the front screws 133 and 134 extend through correspondingly sized holes or into suitably tapped holes in the transverse angle 116, the corresponding screws in the back extend through transverse slots 141, in the rear angles 118, and 70 the angles 131 and 132 are clamped onto angle 118 by means of nuts provided upon the lower ends of rear screws 133 and 134.

From said angles 131 and 132,—substantially flush with the inner faces thereof,—extend down 75

the side rods 135 of the elevator which carry plates 136 and 137 at their lower ends, respectively. The said plates are fastened upon the floor plate 125 by screws 138, which extend through 5 transverse slots 139 in plates 136 and 137 and through longitudinal slots 140 in the floor plate 125. Since rods 135 are in alignment with angles 131 and 132, and the said angles face the goods to be delivered, the rods 120, 123 and 135 circumscribe said goods exactly in the same manner as the angles from which they depend.

It is readily understood that the angles 116 and 118 may be moved towards or away from each other and may be clamped into adjusted positions between the housing H and the base B. The lower ends of the depending rods may be adjusted at a corresponding distance from each other, plate 121 being adjusted to the front or to the back along slot 130. In a similar manner 20 the longitudinal angles 131 and 132 may be adjusted towards or away from the center of the device in a transverse direction, the plates 136 and 137 being fastened upon the floor plate 125 in corresponding positions. The view of Fig. 5 shows the angles 131 and 132 and the corresponding rods to be adjusted as close to each other as possible said angles abutting in that instance upon the ends of angle 119 and the ends of plates 136 and 137 abutting upon each other.

30 The vertically slidable plate 142 is slotted to clear the rods and supports the articles stacked up between said rods in the elevator. At the outer ends of the transverse slots in supporting plate 142 are fastened the ends of cords 143, which extend over pulleys 144 suspended from forks 145 adjustably mounted upon the bottom sides of angles 131 and 132 by means of studs and thumb nuts 146, which are engaged upon the longitudinal slots in said angles 131 and 132. At 35 the free ends of cords 143 counter-weights 147 and 148 are fastened thereon, which are spaced apart by a connecting wire 149, said wire being angularly shaped in order to clear the supporting plate 142, as it plays up and down in the elevator. 40 The counter-weights 147 and 148 tension the supporting plate 142 in an upward direction so that goods stacked up on said supporting plate are elevated between the rods and between the angles, the top article of said stack of goods being pressed 45 into contact with the bottom sides of tracks 103 from which it is laterally removed by the transversely moving lug 104.

I have thus described an elevator which not only facilitates the placement of a new charge of goods into the machine but which also allows ready adjustment of said elevator for goods of various sizes. At the same time the whole elevator may be adjusted longitudinally into alignment with the lug 104 in its normal position of 50 rest of Fig. 1.

The elevator is disposed in the base of the machine which is of course suitably closed and may be provided at the front with another door 149, through which access is given to the elevator and 55 to the correct tokens received and retained in the token collection pocket C in case said pocket is located in the base as described before.

The supporting plate 142 is indicated in dot-dashed lines in elevated position in Figs. 1 and 2. 60 I also show in these views members 150 which extend, upon both sides of the machine, vertically slidably up through the machine, and are connected across near the top of the machine by a transverse member 151. From the transverse member 151 extends up a vertical plate 152, which

extends through the top of housing H between intake I and the wrong token pocket W. The plate 152 and the members 151 and 150 depending therefrom are normally in the positions shown in Figs. 1 and 2 but when the elevator 142 is raised 5 so as to engage upon the bottom ends of vertical members 150, and pushes up the said members while delivering the last articles contained in the elevator, the plate 152 is pushed up and closes the slot 21 in intake I, preventing the insertion of 10 additional tokens, because there are no more goods to be delivered. A legend may be provided upon the front of plate 152 upon the part thereof facing in the lowered position of the drawing back of wrong token pocket W, said legend advising the 15 user that the machine is empty.

The aforementioned fingers 81 and 71,—by means of which the levers 62 and drag lever 77 are angularly set, respectively, in the normal positions of Figs. 1 and 6, for actuation of the 20 machine by correct tokens, form parts of tappets 155, which are rotatably fulcrumed upon a transverse rod 156 extending from side to side of the housing H. The said tappets 155 also comprise arms 157 extending upward from said fulcrum, 25 and are engaged near their free ends by set screws 158, which adjustably extend through a square cross piece 159. By means of the set screws 158, the tappets may be adjusted in such positions that the respectively controlled levers function 30 properly, for instance that the arms 63 of levers 62 hold the gauge 64 in the respective groove 60 in such a position that only correct tokens engage upon and actuate said gauges, whereas false tokens do not engage the gauges and pass thereunder,—or clearing the gauges sidewise as explained below,—racing through the slot 60 into the false token pocket F, which is in alignment with the lower end of the groove 60 when the selector is in the normal position of Fig. 1. Fig. 40 1 shows a false token O7 passing from groove 60 into false token pocket F. Another false token O8 is shown to have arrived in said pocket and to have actuated an alarm therein, publishing the fact that an attempt has been made to actuate 45 the machine by a false token.

The said alarm comprises a stationary bottom contact member 160 and an upper resilient contact member 161, which are pressed into contact by the weight of a false token entering upon the 50 false token pocket F, such a contact being brought about in Fig. 1 by the false token O8 resting on the resilient member 161. The contact member 161 is shown to be grounded at 162, whereas the contact of the bottom contact member 160 is insulated 55 mounted upon respective arm and connects through battery 163 to a bell 164 and said bell will ring until the false token has been removed from the false token pocket F. For that purpose the false token pocket is provided with a 60 lock and door 165 at the front thereof.

When tokens are contained in the selector plates and the user operates handle 48, the plates are swung in clockwise direction, until the rollers 70 are engaged—at the end of the stroke of crank 65 47,—by the adjustable screws 166 which correspond to the number of plates and which are aligned upon a square cross piece 167. This swings the levers 62 in a counterclockwise direction so that the gauges 64 release the tokens held thereby, said tokens racing down in the slot as indicated by token O5 in Fig. 8. The bottom of the false token pocket F extends back towards the selector plates and curvedly extends therearound as plate 168, (Figs. 1 and 11). The said plate 75

168 is provided with slots 69 of the width disclosed in Fig. 11 and of a length corresponding substantially to that of slots 170 indicated in said Fig. 11 in plate 171, and in transverse alignment with the 5 grooves 60 in the plates.

Part of slots 169 is therefore covered up in Fig. 11 by the plate 171. The plate 171 is substantially concentric to and slidably abuts upon the bottom of the curved part of plate 168. Plate 10 171 is retained in such slidable abutment upon plate 168 by means of the plates 172 extending over the front and back thereof. The plate 171 is pressed by springs 173 against the end of arm 82. There is a clearance cut 174 in plate 171 15 where said plate is normally pressed by springs 173 against arm 82.

When the tokens are released from gauges 64 by the action of screws 166 at the end of the clockwise, frontward stroke of the crank 47, as 20 described before, the grooves 60 face the part of the slot 169 which is covered in Fig. 11 by plate 171. If the machine had not been actuated by the tokens before they were thus released,—i. e., if drag lever 77 did not engage upon lug 84,—then 25 the released tokens in the grooves fall onto and are arrested by plate 171 and rest thereon. When the operator then releases the handle 48 and selector plates P rotate in counter clockwise direction back to their normal position, the 30 tokens resting on plate 171 are carried forward over said plate until they drop through slots 169, where said slots are not covered by plate 171 in Fig. 11, into the chute 175. The said chute 175 forms part of refund pocket R and extends to 35 the front of the machine; tokens delivered thereto during the return stroke of the crank 47 drop into the tray 176 of the refund pocket R, from where they may be removed by the operator. Correct tokens are therefore returned to the user 40 of the machine, when the machine was not actuated by said tokens. That is the case, when less than the required number of tokens was inserted. Tokens in excess of the number of tokens required 45 for the actuation of the device find their way into the same pocket, which will be explained later.

When the machine has been properly actuated by the correct number of correct tokens, the drag lever 77 engages upon the idle lever 80, so that the 50 said idle lever participates in the movement imparted by the operator to the selector plates and causes dispensation of goods from the elevator out through the delivery opening D as explained before. But at the same time the arm 82 of the rotating idler lever 80 pushes the plate 55 171, against the tension of spring 173 to the left side (Fig. 11). The narrower part of slot 170 is thereby shifted into alignment with the part of slot 169 which previously was covered by plate 171. That part of slot 169, which previously was 60 closed by plate 171 and which now opens therethrough, faces the chute 177 of the token collection pocket C. The tokens which are released by the gauge 64, after actuation of the device, drop 65 therefore into chute 177 and are delivered to the collection pocket C as indicated by token O9.

In Fig. 8 I indicate that the arm 82 of idler lever 80 also engages upon the curved end 178 of a lever 179 which is fulcrumed at 180 on chute 177, and depresses said lever into a clearance cut in chute 177, against the action of counter weight 181 at the other end of said lever. The part of lever 179 depressed into said clearance cut in chute 177 is so short, that it does not prevent 70 token O5 from dropping past it into chute 177. 75

But it prevents the token O5 from racing down in the chute 177 into collection pocket C. As seen from Fig. 2, the chute 177 is provided with a partition 187, retaining the tokens in an upright position and in alignment with the selector plate P 5 from which they have dropped into the chute. Since the coin O5 is stopped by lever 179 after it has dropped into chute 177 and is thus retained at the upper end of said chute, other tokens which were contained in groove 60 behind token O5 and 10 rest on top thereof will therefore not be able to drop out of the selector plate. During the counterclockwise return stroke of the selector plate such excess tokens are therefore carried forward to the front of chute 177, into the chute 175 15 of the refund pocket R and are returned to the operator. During the return stroke the end of arm 82 also releases the curved part 178 of lever 179, so that weight 181 swings the said lever into counterclockwise direction in a position of rest. 20 This releases the token O5 which was retained by said lever at the upper end of chute 177, and the token rolls through the chute into the collection pocket C.

The cover plate 42 is not shown in Figs. 6, 7, 8, 9 25 and 10. It extends over part of disc 41 and arm 63 and closes the groove 60 upon the face of disc 41 when the machine is assembled thus forming a slot 183, so that the tokens O4, O5 and O6 really race through a slot in the plate P. The manner 30 in which the gauge 64 and the arm 63 are disposed in said slot 183, and the manner in which tokens pass through said slot under specific conditions are indicated in Figs. 12 and 13. The groove 60 35 extends into the disc to a depth substantially corresponding to the thickness of a correct token. If therefore a correct token races through slot 183 along the side 182 of said slot which is the bottom of the groove 60,—the token will normally 40 follow such a path under gravity,—the token is engaged upon one edge of its circumference by the concave edge 67 of gauge 64. The said edge 67 is attenuated to such an extent that it does not engage upon a token following the side 182 of 45 the slot when the said token is of less than the thickness of the correct token. Such a false token of insufficient thickness races therefore past the edge 67 of the gauge 64,—possibly swinging said gauge out of the way,—into the false 50 token pocket F where it gives an alarm indicating that an attempt has been made to actuate the device by a false token.

In Fig. 12 we notice that the slot 183 formed by the groove in the disc and the cover widens out 55 upon the inside of the plate P and is narrowed down again at its exit. The slot 183 is wider where the gauge is disposed therein and there a magnet 184 is countersunk into the cover 42; of course it also may form an integral part of said 60 cover in which case the cover is suitably, preferably permanently, magnetized.

Tokens are normally made of semi-valuable or 65 precious metal, but not of iron. False tokens or slugs are frequently made of iron, ferrous metal, or are otherwise magnetizable. Such magnetizable false tokens will not follow the side 182 of slot 183 in racing through said slot, but will be pulled over to the opposite side of said slot by magnet 184, racing through the slot along the 70 said side 185 of the slot. The magnetizable false token is of course of the same width or of less width than the correct token, because otherwise the said token could not have been inserted through the device through the intake. Since 75

the side of slot 183 is removed from edge 67 to a distance equal to or exceeding the thickness of the correct token, the said magnetizable false token,—following wall 185,—is not engaged by 5 gauge 64, races through slot 183 and drops into the false token pocket F where it actuates the alarm.

Gauge levers 62 may be made so sensitive by adjustment of the tension applied thereto and by 10 an accurate setting of fingers 71, that underweight tokens do not actuate the mechanism although they are engaged by the gauges, correct weight tokens actuate the device, and overweight tokens momentarily lift the gauges into actuating position 15 but immediately release them again, because they are too heavy to be retained by the gauges in the actuating position and slip, due to gravitational force, out again from under the gauge, and race through the slot into the false token 20 pocket.

But the device is also operable when less sensitively adjusted,—though not differentiating the tokens by weight,—the gauge merely arresting the token without being lifted thereby into an actuating 25 position. The finger 71 then lifts the gauge when operation is begun, the token sliding a very short distance under the gauge and blocking it in the lifted position, in which lever 62 engages and actuates the drag lever 77, after finger 81 has released the said drag lever.

Although I have shown and described one form of embodiment of my invention in detail, yet I do not wish to be limited thereby, except as the state of the art and the appended claims may require, 30 for it is obvious that various modifications and changes may be made in the form of embodiment of my invention, without departing from the spirit and scope thereof.

What I claim is:—

40 1. In a device actuated by a token of predetermined width, in combination with an intake, a rotatable selector plate with a slot extending therethrough, said slot normally communicating with said intake and a token delivered from said intake to said slot being adapted to race through said slot, and an oscillatable gauge offsetedly disposed in said slot and engaging upon one edge of the circumference of said token of predetermined width gravitationally racing into said slot, tokens 45 of less than said predetermined width, which gravitationally race into said slot, clearing and racing past said gauge.

50 2. In a token-actuated device, a selector plate with a slot extending therethrough, a correct token racing gravitationally through said slot on one side thereof, a gauge of limited width in said slot engaged by a correct token gravitationally racing through said slot and actuating said device

when thus engaged, and magnetic means comprised in said plate on the other side of said slot opposite to the said one side and redirecting magnetizable tokens racing through said slot to a path along said other side of said slot, said slot being of such width at the point where said gauge is disposed therein, that said redirected tokens racing through said slot along said other side thereof clear and race past said gauge. 5

3. In a token-actuated device, a selector plate, 10 comprising a disc with a straight groove extending across the face of said disc, said groove substantially clearing in width a token racing therethrough, a lever fulcrumed upon said face of said disc and extending over said groove, a gauge 15 mounted on said lever, extending into said groove, engageable by a token racing through said groove and actuating said device by way of said lever when thus engaged, and a cover removably extending over said groove in said disc and over said lever and forming with said groove a slot guiding 20 said tokens.

4. In a token-actuated device, in combination with rotatable slotted selector plates, levers mounted on said plates, gauges depending from 25 said levers into said slots and predeterminedly engaging upon tokens racing through said slots, and rollers mounted on said levers, tappets rotatably mounted on said device, fingers comprised in said tappets and disengaging and engaging said rollers 30 when said plates are rotated, arms comprised in said tappets and extending to the top of said device, and adjustable means on said device predeterminedly stopping said arms, setting said tappets and regulating the engagement of tokens 35 racing through said slot by said gauges.

5. In a token-actuated device, rotatable slotted selector plates, means for manipulating said plates, means actuating said device, when the correct number of correct tokens is delivered into the 40 slots in said plates and when said plates are manipulated, a false token pocket, a refund pocket, and a collection pocket alternately aligned with the slots in said manipulated plates, and means releasing from the slots of said manipulated plates false tokens, wrong change, and the tokens 45 actuating said device to said pockets, respectively.

6. In a token-actuated device, rotatable selector plates provided with slots, means for manipulating said plates through an operating cycle, a 50 collection pocket communicating with said slots during an operating cycle, the tokens by which said device was actuated dropping from said slots into said pocket, and means retaining in said slots tokens in excess of the tokens required for actuating said device. 55

EDWIN J. BROWN.
